D12-20. OR D 13,407 EX

NO. 13,407

NOV. 14, 1882

UNITED STATES PATENT OFFICE.

JOHN L. POPE, OF CLEVELAND, OHIO.

DESIGN FOR A WHIFFLETREE-PLATE.

SPECIFICATION forming part of Design No. 13,407, dated November 14, 1882.

Application filed August 24, 1882. Term of patent 14 years.

To all whom it may concern:

Be it known that I, JOHN L. POPE, of Cleveland, in the county of Cuyahoga and State of Ohio, have invented and produced a new and original Design for Whiffletree-Plates, of which the following is a specification, reference being had to the accompanying engraving, forming part thereof.

My invention relates to a design for whiffletree-plates; and it consists in certain features of configuration, which will be hereinafter more fully described and claimed.

The engraving which accompanies this specification shows the two parts A and B of a whiffletree-plate. The part or half A is made with a central ring or annulus, *a*, and a smaller ring, *b*, within it and immediately surrounding the bolt-hole. On each side of the ring *a* is an ear-piece with two holes, through which to pass screws to fasten the plate to its proper and desired part of the vehicle. The contour of each ear-piece is like the other, and a description of one will suffice. The extremity is

rounded, then the edges curve inwardly, as at *c*, then run outwardly, then inwardly, and gradually outward again until they meet the ring *a*. A projection, *i*, is formed on each edge where inward and outward curves meet. The part B has the usual pivot-bolt hole, and has two ear-pieces alike in contour and similar in every particular to those on the half A. It also has an annular boss, *e*, which fits in between the rings *a* and *b* when the parts are put together for use.

I claim as my invention and would like to 35 secure by Design Letters Patent—

1. The part A, having ring *a* and ear-pieces, curved as shown and described.
2. The part B, with ear pieces, curved as shown and described.

In witness whereof I have hereunto set my hand this 5th day of August, 1882.

JOHN L. POPE.

In presence of—

J. R. CURRIER,
J. M. ODELL.
